UNITED STATES PATENT OFFICE

161,651

CONDIMENT SHAKER

Richard W. Rosche, Akron, Ohio

Application May 29, 1950, Serial No. 10,258

Term of patent 14 years

(Cl. D44—22)

To all whom it may concern:

Be it known that I, Richard W. Rosche, a citizen of the United States, residing at Akron, in the county of Summit and State of Ohio, have invented a new, original, and ornamental Design for a Condiment Shaker, of which the following is a specification, reference being had to the accompanying drawing, forming part thereof.

The appearance of the rear of the article, not shown in the drawings, is substantially the same as the appearance of the front portion as shown in the drawings.

The dominant features of the design reside in the portions shown in full lines.

I claim:

The ornamental design for a condiment shaker, as shown and described.

RICHARD W. ROSCHE.
